BURIAL VAULT

Filed Jan. 6, 1930

INVENTOR
THOMAS F. JETER
BY
Cook & Robinson
ATTORNEY

UNITED STATES PATENT OFFICE

THOMAS F. JETER, OF TACOMA, WASHINGTON

BURIAL VAULT

Application filed January 6, 1930. Serial No. 418,671.

This invention relates to improvements in burial vaults and it refers particularly to vaults of that character known as "surface vaults" and which embody one or more dead air spaces above the sealed casket chamber; the present invention being in the nature of an improvement on the vault construction disclosed in United States Patents, Numbers 1,532,313 and 1,391,386, issued to me on 10 April 7, 1925, and September 20, 1921, respectively.

It is the principal object of the present invention to provide a vault that is of more satisfactory construction than those of the 15 patents above referred to, especially in the formation of the dead air chamber and the sealing of this chamber and the casket chamber.

In the construction of the earlier patent, 20 above mentioned, the sealing of the joint between the cover plate and vault walls was not entirely satisfactory, for the reason that the position of the joint permitted moisture to seep in and any freezing then resulted 25 in opening the seam, thus finally permitting seepage into the dead air space.

In the second patent, above referred to, 30 the joint was better sealed by reason of setting the cover plate down into fresh concrete held in place by a wooden form, but it has been found that the form sometimes expands and causes loosening of the joint with the ultimate result of seepage entering 35 the dead air chamber.

The present invention has for its object 40 to provide a surface vault in which all the desirable features of the two vaults previously patented by me are embodied, and in which a new method of construction is followed which makes possible a positively and permanently sealed casket and dead air chamber.

Other objects of the invention reside in 45 the details of construction and combination of parts as will hereinafter be described.

In accomplishing these and other objects, 50 I have provided the improved details of construction, the preferred forms of which are illustrated in the accompanying drawings, wherein—

Figure 1 is a longitudinal section, of a burial vault constructed according to details of the present invention.

Figure 2 is a cross section taken on line 2—2 in Figure 1. 55

Figure 3 is a plan or top view, with parts broken away for better illustration.

Referring more in detail to the drawings—

The vault body is of rectangular form and comprises opposite end walls 1 and 2, opposite side walls 3 and 4, and a bottom wall 5, all of which are preferably integrally cast from suitably reenforced concrete, other suitable material sufficiently thick to give the desired strength and durability and to be 60 water and air tight. 65

The upper portions of the side and end walls are of less thickness than the lower portions, thereby providing an upwardly facing seat or shoulder 6 entirely about the 70 inner surface of the vault for the support of an upwardly crowned slab 7 of concrete, or the like, which is designed to cover the casket chamber 8 formed by the lower portion 75 of the vault.

After the casket has been placed in the vault, and the cover slab 7 placed on the shoulders, the chamber is sealed by a layer of wet concrete being poured over the slab. 80 This layer of concrete, as designated at 10, is of sufficient thickness to positively seal the joint about the side and end walls and will give added strength and durability to the vault.

After the sealing of the casket chamber 85 has been completed, a form is placed on the concrete seal 10 for the formation of a dead air chamber above the casket chamber; the advantages of which were fully disclosed in 90 my prior patents. This form, preferably would be of concrete or other material that is not effected by moisture, and comprises a horizontal top wall 12, opposite side walls 13—13, and opposite end walls 14—14; the 95 side and end walls are parallel with but spaced inwardly from the side walls of the vault and the top wall 12 is somewhat below the level of the top edge of the walls of the vault. Beneath the wall 12 and bounded 100

by the walls 13—13 and 14—14 is the dead air chamber 15.

After this form has been placed in position it is covered over with a layer of plastic concrete 16 which also fills the spaces between the vault walls and side and end walls of the form, as at 17, to positively seal the dead air chamber and thus provide additional sealing for the casket chamber.

10 The top surface of the concrete layer 16 is practically level with the top edges of the side and end walls of the vault, and overlying this is a cover slab 18 which rests about its edges upon the vault walls and has a depending flange 19 extended down within the vault walls to prevent its being displaced. This cover is placed in position before the concrete layer 16 has set, so that the flanges 19 will embed themselves. It is sometimes 15 desirable to place some sort of separator about the flanges so that the cover slab may be lifted off in case it is desired to replace it, also to provide for expansion of air thus dispensing with ventilating tubes.

20 25 In its preferred form, the cover slab has a centrally arched portion 16a providing an air space 20 beneath it. It also is provided with an inclined head portion 22 for receiving a marker 23 as shown in Figure 1.

30 35 By so constructing the vault, the undesirable results from use of wooden forms are eliminated, and a positively sealed dead air and casket chamber results. Even though the seam between the cover and vault walls is under ground or water, no water can possibly seep through and into the casket chamber.

40 It is apparent that minor changes in the details of construction might be made without departing from the spirit of the invention, and for this reason it is not desired that the claims be limited only to those shown but that they broadly cover the device commensurate with the invention.

45 Having thus described my invention, what I claim as new therein and desire to secure by Letters-Patent, is:

1. In a vault of the character described, a casket chamber having an overlying sealing slab, a form disposed upon the slab having a top wall and having side and end walls spaced inwardly from the side and end walls of the vault, and a sealing slab of plastic concrete filled over and about the form and filling the spaces between its side and end walls and the vault walls to seal the vault and forming a sealed dead air chamber within the form.

2. In a vault of the character described, comprising opposite side and end walls and a bottom wall forming a casket chamber within the lower portion of the vault; said side and end walls having shoulders about their inner surfaces, a cover slab for the casket chamber resting on said shoulders, a sealing slab of plastic material overlying the

said slab, a form disposed upon the said sealing slab and comprising a top wall and opposite side and end walls which are spaced inwardly from the side and end walls of the vault, and a sealing slab of plastic concrete 70 filled over and about the form and filling the spaces between its side walls and the vault walls and providing a sealed dead air chamber within the form.

3. In a vault of the character described, 75 comprising opposite side and end walls and a bottom wall forming a casket chamber within the lower portion of the vault; said side and end walls having shoulders, about their inner surfaces, a cover slab for the casket chamber resting on said shoulders, a sealing slab of plastic material overlying the cover slab, a form disposed upon the said sealing slab and comprising a top wall and opposite side and end walls which are spaced inwardly from the side and end walls of the vault, a sealing slab of plastic concrete 80 filled over and about the form and filling the spaces between its side walls and the vault walls and providing a sealed dead air chamber within the form, 85 and a cover slab overlying the vault and having flanges formed on its under side to fit within the side and end walls of the vault and to embed themselves in the plastic sealing slab; said cover slab being arched upwardly to form an air space between it and the sealing slab of the dead air chamber.

Signed at Seattle, Washington, this 20th day of December, 1929.
